UNITED STATES PATENT OFFICE

BURKE M. BAXTER, OF GRAND RAPIDS, MICHIGAN

PAPER PULP BEATING MACHINE

Application filed October 3, 1929. Serial No. 397,010.

The present invention relates to paper-pulp beaters, such as are employed in paper making mills; and its object is, generally, to provide an improved machine of that character; and more particularly, to provide an improved construction and combination of parts in such a machine; and further, to provide such a construction wherein plastic or concrete bottoms are combined with vertical walls of metal or wood in forming the circuitous pulp-channel of the machine; and further, to provide such a channel in which the radii of the turns thereof are increased and the cross-sectional dimensions of successive portions of such channel are so correlated with each other and with the vertical inclination of their bottoms that economy of space is effected and the flow of the paper pulp through said channel is made uniform; and further, to thus construct said channel and its successive portions and turns that lodgment of the paper pulp therein is eliminated or minimized.

These and any other and more specific objects hereinafter appearing are attained by, and the invention finds preferable embodiment in, the structure hereinafter particularly described in the body of this specification and illustrated by the accompanying drawings, in which:

Figure 1 is a top plan view of a paper-pulp beater;

Figure 2 is a side elevational view thereof;

Figure 3 is a transverse sectional view of the same taken on a vertical plane corresponding to line 3—3 of Figures 1 and 2;

Figure 4 is a transverse sectional view of the same taken on a vertical plane corresponding to line 4—4 of Figures 1 and 2;

Figure 5 is a longitudinal sectional view of a portion of said machine taken on a vertical plane corresponding to line 5—5 of Figure 1; and

Figure 6 is a longitudinal sectional view of a portion of the same taken on a vertical plane corresponding to line 6—6 of Figure 1.

In these drawings a beating machine of the "Horne" type, such as is employed in paper making mills is shown, comprising a circuitous channel designated generally 1, and at

one end of the machine a rotatable beater roll 2 of common form having a shaft 3, which roll extends downwardly into the channel and, cooperating with the member or bed plate 4 in the bottom of the channel, serves to break up the paper pulp into small portions and assists in the maceration thereof, and also causes the macerated pulp to flow along the channel in the direction of the arrows shown therein, by raising the pulp over the top of the roll from the lower portion 5 of the channel to and into the higher upper end of portion 6 of the channel whose bottom 7 inclines downwardly toward said portion 5 adjacent the turn 8 of the channel. The pulp mass is thus given a circuitous movement through the channel. The bearings 9 in which the roll's shaft 3 turns may be raised or lowered relatively to the member 4 by well known means indicated in the drawings and for purposes well understood in the art.

In machines of this character considerable difficulty is encountered in moving the entire mass of pulp through the channel, owing to a tendency of portions of the pulp to lodge along the sides of the channel particularly at turns thereof. This difficulty arises from the fact that in such machines generally, changes in direction of flow are effected by angular deviations in the channels since the walls of the channels are in the main flat surfaces with intervening angles rather than non-angular curved surfaces which would insure easier and more gradual changes in path of flow; and also from the fact that the cross-sectional dimensions of certain portions of the channel are not so well related to such dimensions of other portions; and also to the fact that the vertical inclination of the bottoms of such portions are not properly correlated.

To properly correlate the cross-sectional dimensions of the various portions of the channel and the vertical inclination of their bottoms is therefore one of the principal objects of this invention.

It will be understood that the pulp mass having been raised by the roll 2 over the top thereof to enter the upper end of channel portion 6, the mass will flow along said portion 100

(whose bottom 7 is considerably inclined downwardly) more rapidly than the mass will flow along the channel portion 5 (when the mass passes thereto) because the downward inclination of the bottom 10 of portion 5 is much less than that of the bottom of channel portion 6. Therefore the width of portion 6 may be considerably less than that of portion 5, and yet an equal amount of pulp will pass through each of the channel's said portions in the same length of time. It will also be understood that by dividing the entire width of the machine into such two portions 5 and 6 of properly related width, the horizontal space occupied by the entire machine may be economized. It is therefore an important feature of this invention that, in a beating machine of given width, the "mid-feather" or partition 11 between portion 6 (whose bottom 7 has the greater vertical inclination) and portion 5 (whose bottom 10 is relatively of less vertical inclination) is so located that said portion 6 is narrower than said portion 5, as well shown in Figure 1. Moreover, by thus locating the mid-feather nearer to the vertical wall 12 of the machine and farther from its opposite vertical wall 13, the portion 5 of the channel adjacent the rotatable roll 2 is made more nearly straight than it could be if the mid-feather 11 were located nearer the wall 13 of the machine. This is apparent in Figure 1, where the channel's turn 14 (through which the pulp passes from channel portion 5 to the rotatable roll 2) is at one side defined by curve 15 in the vertical wall 16 (a continuation of the mid-feather), such curve being not so abrupt (or of such short radius) as would be necessary if the mid-feather were nearer the wall 13 of the machine and the channel portion 5 therefore narrower.

In forming the pulp channel of this machine, plastic (concrete) parts are advantageously combined with metallic or wooden parts. As particularly well shown in the cross-sectional views (Figures 3, 4, 5 and 6) the bottom of the channel, except for that cross part 17 of portion 6 through which part the pulp (after being raised by the rotatable roll 2) passes, is made of plastic material—cement—and the "forms" between which it is poured are the vertical walls of the machine, including the mid-feather or partition wall 11. These walls may be wooden or metallic plates as shown. Thus, in making the body of this machine (i. e. the pulp channel thereof) it is only necessary to frame the vertical walls (as the metallic plates shown) and pour the concrete between them, shaping the bottoms of the channel portions to the proper inclination, and desirably forming curved corners at their sides as illustrated. However, these vertical walls of the channel may, of course, be made of concrete as well as the bottoms.

The invention being intended to be pointed out in the claims, is not to be limited to or by details of construction of the particular embodiment thereof illustrated by the drawings or hereinbefore described.

70

I claim:

1. In a paper-pulp beating machine of the character described, a channel for flowing the pulp therethrough comprising successive portions, the first portion venting into the second portion and having less cross-sectional dimensions than the second portion and a bottom longitudinally inclined from the horizontal at a greater angle than is the bottom of the second portion, the cross-sectional dimensions of said portions being so related to each other and to said angle of inclination that a given amount of pulp will flow in a given time through said portions respectively, and a beater roll at one end of the machine for raising the pulp over said roll from the second portion to the first portion.

75

2. In a paper-pulp beating machine, a channel for flowing the pulp therethrough having a mid-feather dividing the channel into successive portions, the first portion venting into the second portion and having a bottom longitudinally inclined downwardly thereto at a greater angle from the horizontal than the bottom of the second portion inclines downwardly, the mid-feather dividing the channel into a horizontally wider second portion and a horizontally narrower first portion and the width of said portions being so related to each other and to said angle of inclination that a given amount of pulp will flow in a given time through said portions respectively, and a beater roll for raising the pulp over the top of said roll from the second portion to the first portion.

80

3. In a paper-pulp beating machine of the character described, a channel for flowing the pulp therethrough comprising successive parallelly-disposed portions connected by curved portions, one of said parallel portions having less cross-sectional dimensions than the other parallel portion and having a bottom longitudinally inclined from the horizontal at a greater angle than is the bottom of said other parallel portion, the cross-sectional dimensions of said parallel portions being so related to each other and to said angle of inclination that a given amount of pulp will flow in a given time through said parallel portions respectively, and a beater roll for raising the pulp over said roll from one of said parallel portions to the other parallel portion.

85

In testimony whereof I have hereunto set my hand at Grand Rapids, Michigan, this 14th day of August, 1929.

BURKE M. BAXTER.
